UNITED STATES PATENT OFFICE.

JOSEPH HALDEN, OF MANCHESTER, ENGLAND.

FASTENING FOR CANVAS APRONS EMPLOYED IN CERTAIN DESCRIPTIONS OF PHOTOPRINTING-FRAMES.

SPECIFICATION forming part of Letters Patent No. 683,040, dated September 24, 1901.

Application filed February 25, 1901. Serial No. 48,845. (No model.)

To all whom it may concern:

Be it known that I, JOSEPH HALDEN, a subject of the King of Great Britain and Ireland, residing at 8 Albert Square, Manchester, in the county of Lancaster, England, have invented a new and Improved Fastening for Canvas or Like Aprons Employed in Certain Descriptions of Photoprinting Apparatus, (in respect whereof I have applied for a patent in Great Britain to bear date January 10, 1901, No. 703,) of which the following is a specification.

This invention relates to photoprinting apparatus of the character wherein a drum or cylinder formed of transparent material is mounted on trunnions, so as to be capable of rotation about its transverse axis, a lamp or other source of light entering the interior of the drum, while the drawings to be reproduced, together with the sensitive paper, are secured upon the exterior surface thereof.

My improvements have special reference to means for securing the canvas aprons or jackets which serve to retain the tracings, together with the sensitized paper, upon the exterior surface of the glass or other transparent drum or cylinder about which they are arranged while undergoing reproduction.

In the accompanying drawings, Figure 1 is a view illustrating photoprinting apparatus of the character to which my improvements are applicable. Fig. 2 is a transverse section, and Fig. 3 a plan, of the drum or cylinder drawn to a larger scale. Fig. 4 is an elevation of a portion of a spindle furnished with hooks or fingers for engaging with the rod or lath in the edge of the apron, Figs. 5 and 6 being transverse sections showing different forms of hooks or fingers. Fig. 7 is an elevation of a spindle or bar formed with cranked portions; and Figs. 8 and 9 are transverse sections, respectively, of a shaped bar and a built-up bar, each having a longitudinal fin.

In order that my improvements may be properly understood, it will be necessary to explain the general construction of the apparatus illustrated in Fig. 1 and the mode of working the same.

The apparatus comprises a cylindrical structure formed of two semi or approximately semi cylindrical portions *aa* of glass

or other suitable transparent material, the extremities of each portion *aa* being mounted in heads *b b*, whereof the grooves are furnished with caoutchouc or other yielding packing. The heads *b b* are connected together by pairs of bars or tubes *c c*, arranged on each side of the structure adjacent to the opening which occurs between the longitudinal edges of the transparent portions *aa*. The cylindrical structure is mounted in a frame *d* by means of trunnions, one of which, *e*, carries a plate *f*, formed with holes for the insertion of a retaining-pin and adapted to register with holes formed in the framing *d*. The electric-arc lamp *g*, which is adapted for being raised and lowered according to the requirements of the work under reproduction, is admitted into the cylinder through the central opening in whichever of the heads *b b* is uppermost.

In working the apparatus, assuming a drawing prepared on tracing-paper is to be reproduced by the ferricyanid or like photographic process and that the cylinder is in the position indicated by broken lines in Fig. 1, the tracing is laid upon the upper surface of the cylinder and the sensitized paper placed upon the rear side of the tracing, a canvas or other apron *h*, secured about the cylinder by means of clips, serving to retain the tracing and the sensitized paper in position during the process of printing. By turning the cylinder the opposite side may be similarly utilized. The cylinder thus equipped is then turned through an angle of ninety degrees, a retaining-pin being inserted through one of the holes in the plate *f* and passed into the coinciding hole in the framing. The cylinder is hereby retained in the position indicated in full lines in Fig. 1. The lamp is now lowered into the cylinder, whereupon the process of reproduction commences.

In securing the canvas apron in position according to my improved method I employ spindles *i*, which extend the entire length of the cylinder *aa* and which are rotatably mounted in the heads *b b*, wherein the cylinder terminates. Each spindle is furnished at intervals with hooks or fingers *i'*, which engage with a rod or lath *h'*, wherewith the edge of the apron *h* is furnished. Each spin-

dle i is provided at one end or at each end with a ratchet k and releasable pawl k' , which operate to hold the spindle i in the position to which it may have been rotated, and thus 5 to maintain the apron h at the required tension.

- Instead of furnishing the spindle with hooks or fingers i' , as shown in the detached views, Figs. 5 and 6, the portion thereof which engages with the lath or rod h' in the edge of the apron may be continuous throughout the length of the spindle, the engagement being under such circumstances continuous instead of intermittent.
- 15 The spindle may consist of a rod upon which the hooks or fingers are mounted and secured, as shown in Fig. 4, or it may consist of a bar i , formed with one or more cranked portions i^2 , Figs. 1, 2, and 7, or it may consist of a bar i^0 , formed or provided with a longitudinal fin i^3 , which projects laterally and engages with the lath or rod h' in the edge of the apron h . It will be observed that at suitable distances along the lath h' hooks 25 or bent plates h^0 are attached for affording a hold for the fin i^3 . A shaped bar or spindle of the section last referred to may be built up of a plate i^3 , secured between two half-round or other suitable stiffening-bars i^4 i^4 , the plate 30 i^3 projecting on one side and forming a rib adapted for engaging with the lath or rod h' , as shown in Fig. 9. l is a detachable handle

wherewith either of the spindles i may be rotated.

With a view to enabling the tension of the 35 apron h to equalize itself its back edge may be provided with a rod h^2 and be attached by means of tension-springs h^3 to the adjacent bars c , pertaining to the heads b b .

What I claim as my invention, and desire 40 to secure by Letters Patent, is—

1. In photoprinting apparatus, the herein-described means for securing the canvas aprons in position upon the printing-cylinder, consisting of spindles rotatably mounted 45 in the heads pertaining to the cylinder and having catches thereon to engage with the edges of the apron.

2. For securing the canvas aprons in position in photoprinting apparatus, a spindle, 50 extending along the printing-cylinder, rotatably mounted in the heads of the latter, and having laterally-formed projections adapted, upon the spindle being rotated, to engage the rod wherewith the apron is furnished, 55 and to hold the apron in tension, substantially as herein described.

In testimony whereof I have signed my name to this specification in the presence of two subscribing witnesses.

JOSEPH HALDEN.
